UNITED STATES PATENT OFFICE.

LAWRENCE F. MARTIN, OF KENOSHA, WISCONSIN.

GARBAGE-WAGON.

1,135,602.

Specification of Letters Patent. Patented Apr. 13, 1915.

Application filed July 18, 1913. Serial No. 779,714.

To all whom it may concern:

Be it known that I, LAWRENCE F. MARTIN, a citizen of the United States, and resident of Kenosha, in the county of Kenosha and State of Wisconsin, have invented new and useful Improvements in Garbage-Wagons, of which the following is a description, reference being had to the accompanying drawings, which are a part of this specification.

10 This invention relates to improvements in garbage wagons.

It is one of the objects of the present invention to provide a garbage wagon having separate compartments for containing wet and dry garbage which may be independently handled.

20 A further object of the invention is to provide a garbage wagon in which the wet garbage compartment is constructed in a novel manner to form water tight joints to prevent leakage of the moisture from the garbage contained therein.

25 A further object of the invention is to provide a garbage wagon in which the discharge door of the wet compartment is so constructed that it may be easily opened and closed and when closed the joints of the door and the casing are formed water tight.

30 A further object of the invention is to provide a garbage wagon in which the securing means for the doors of the compartments are located exteriorly of said compartments so that the contents of the compartment cannot in any manner injure the same.

35 A further object of the invention is to provide a garbage wagon of simple construction which is strong and durable and is well adapted for the purpose desired.

With the above and other objects in view 40 the invention consists of the improved garbage wagon and its parts and combinations as set forth in the claims, and all equivalents thereof.

45 In the accompanying drawings in which the same reference characters indicate the same parts in all of the views: Figure 1 is a side view of the body portion of the improved garbage wagon; Fig. 2 is a vertical longitudinal sectional view thereof; Fig. 3 is a rear end view of the body portion; and Fig. 4 is a transverse sectional view taken on line 4—4 of Fig. 1.

50 Referring to the drawings the numeral 8 indicates the bottom portion of the wagon, 9 the sideboards thereof, 10 the front end portion and 11 the top. The upper forward

portion of the body is provided with a seat 12 and a foot rest 13 and the lower side portions of the body are provided with steps 14 for convenience in reaching the upper portion of the wagon body and the seat. The box body is divided medially by a fixed transverse partition 15 to form a forward compartment 16 for dry garbage and a rear compartment 17 for wet garbage, the front, 60 sides and bottom portions of the wet garbage compartment being lined with sheet metal 18 to form a water tight inclosure. The upper portion of the dry garbage compartment 16 is inclosed by a plurality of hinged doors 19 and the wet garbage compartment is similarly closed by hinged covers 20.

65 The rear end or tail board of the wet garbage compartment is in the form of a door or gate 21 which is pivoted at its upper end to the side portions 9 of the body by angled pivot bars 22. A rubber sealing strip 23 secured to the body and interposed between the body and the lower and side edges of the tail-board door or gate 21 serves to 70 form a water tight connection between the parts mentioned. In order to permit the tail-board door to be tightly clamped in position the angled pivot bars 22 extend through slots 24 in the side portions 9 and locking means 80 comprising threaded rods 25 extending vertically through reinforcing members or timbers 26 have a threaded engagement with a bottom locking member or a metal bar 26' positioned beneath and carried by the bottom 85 portion of the body. The upper ends of the threaded rods are bent to form cranked portions for convenience in turning the rod into and out of threaded engagement with said bottom locking member or metal bar 26'. 90 The side portions of the body may also be drawn tightly into engagement with the tail-board door by transversely extending locking means comprising bolts 27 which extend through the sides 9, the reinforcing 95 members or timbers 26 and are threaded into one of the locking members or brace bars 28 forming part of the sides 9. The brace bars 28 have threaded lower ends which pass through apertures in the bar 26' to which 100 they are secured by nuts 28'.

105 The dry garbage is discharged from its compartment 16 through the side doors 29 which are hinged at their upper edge portions to the sides 9 and are provided with bolts 30 for securing their lower edge portions. These locking bolts 30 are pivotally

and slidably carried by locking members 31 which are fulcrumed on the doors and are provided with horizontally projecting arms 32 to which the bolts are connected and also 5 with depending handles 33 for swinging the same. The lower ends of the bolts lockingly engage plates 34 projecting horizontally from the bottom portion of the body.

In use the dry garbage and the wet garbage 10 are placed in their respective compartments through the upper doors and are discharged through the side and tail-board doors.

From the foregoing description it will be seen that the improved garbage wagon is of 15 simple construction, is strong and durable and is well adapted for the purpose desired.

What I claim as my invention is:

1. In a garbage wagon, a compartment having sides and a bottom, an end gate pivotally secured to said sides and having reinforcing members secured thereto, a locking member disposed adjacent the bottom of said compartment, locking means passing through said reinforcing members 20 and connected to said locking member to lock said gate to the bottom of said compartment, locking members disposed adjacent the 25

sides of the compartment and secured to the bottom locking member, and locking means passing through said reinforcing members 30 and connected to said side locking members to lock said gate to the sides of said compartment.

2. In a garbage wagon, the combination with a compartment having sides and a bottom, of an end gate pivotally secured to said sides, means for locking said gate to the sides of the compartment comprising a brace bar adjacent one side of the compartment and transversely extending bolts passing through 40 the sides of the compartment and said gate and having threaded engagement with said brace bar, and means for locking the gate to the bottom of the compartment comprising a bar disposed adjacent said bottom and 45 a plurality of rods passing through said gate and bottom and having threaded engagement with said bar.

In testimony whereof, I affix my signature, in presence of two witnesses.

LAWRENCE F. MARTIN.
